Fig. 3

Fig. 4

Fig. 5

Fig. 6

FIG. 1 is a side elevational view of a knife embodying the present design.

FIG. 2 is a similar view showing the knife as it appears from the side opposite to that shown in FIG. 1.

FIG. 3 is a top plan view thereof.

FIG. 4 is a bottom plan view thereof.

FIG. 5 is a sectional view taken along line 5—5 of FIG. 2.

FIG. 6 is a similar view taken along line 6—6 of FIG. 2.

The dominant features of this design are shown in full lines.

I claim:

The ornamental design for a knife, as shown and described,
